UNITED STATES PATENT OFFICE.

JOHN F. MAEDER, OF CHICAGO, ILLINOIS.

VENT.

SPECIFICATION forming part of Letters Patent No. 417,435, dated December 17, 1889.

Application filed October 8, 1889. Serial No. 326,311. (No model.)

To all whom it may concern:

Be it known that I, JOHN F. MAEDER, a subject of the Emperor of Germany, residing at Chicago, in the county of Cook and State 5 of Illinois, have invented a new and useful Improvement in Vents, of which the following is a specification.

My invention relates to an improvement in the class of vents used with barrels to allow 10 air to pass in as the liquid contents are drawn off, and more especially with barrels containing liquids charged with carbonic-acid gas, as beer, ale, and the like, to permit the ingress of air necessary to produce the internal pressure for effecting the discharge of 15 the liquid contents on opening the faucet, but without permitting the escape of carbonic-acid gas through the vent-opening either during such discharge or while the 20 faucet is closed.

The object of my improvement is to provide such a vent of simple construction, which shall permit ready access to its parts for 25 cleansing purposes, and which shall serve effectively its purpose and particularly in its function of preventing the contents of the barrel on which it is used from becoming "flat" by losing its enlivening constituent—carbonic-acid gas.

30 In the accompanying drawings, Figure 1 shows my improved vent in elevation, and Fig. 2 is a vertical longitudinal section of the same.

The vent A involves a hollow body portion r, 35 which should taper, as shown, from near its upper closed end to its opposite open end, or at least be contracted toward the end which is driven into the vent-opening in the barrel or keg, and a tubular branch q, extending at an 40 angle (preferably a right angle) from near the enlarged end or head of the body-portion r, the branch q being closed at its outer extremity and containing in its under side a screw-plug p, having a central opening o, in which extends the stem n' of a valve n, having its seat 45 in the inner end of the opening o.

The device may be formed of any suitable metal; but I prefer to cast it of malleable iron, with the branch q integral with the body portion, but then in the form of a solid 50 extension, requiring subsequently to be bored out. The boring is performed from the outer end of the branch, and thus affords an opening entirely through it, requiring that it be closed at the outer end. To effect this closing, I prefer to use a screw-plug m, since the latter is easily adjustable and removable to permit ready cleaning of the interior of the branch and body portion.

For the more thorough cleansing of the device, which may be required periodically, it should, while separate from any receptacle with which it is designed for use, have steam blown through it, which is most readily accomplished by introducing the steam at the 65 contracted open end of the part r after having removed the plug p or m, or both plugs.

As will be understood from the foregoing description and inspection of the drawings, the device when driven into the vent-opening of a barrel normally seals such vent-opening, since the valve n is then against its seat; but that when the faucet is opened to draw off the contents the valve is raised by the influx of air to close only when the 75 faucet is turned off.

What I claim as new, and desire to secure by Letters Patent, is—

A vent A, comprising, in combination, a body portion r, having a lateral tubular extension q, provided with a lateral opening containing an adjustable and removable plug p, having an opening o, a valve n, seated in the tubular extension over and having its stem n' in the opening o, and a plug m, removably inserted into the outer end of the extension q, substantially as described.

JOHN F. MAEDER.

In presence of—
J. W. DYRENFORTH,
M. J. FROST.
